United States Patent Office

Des. 186,212
Patented Sept. 29, 1959

186,212

AUTOMOBILE BODY

Louis L. Gagnon, Southbridge, Mass., assignor to American Optical Company, Southbridge, Mass., a voluntary association of Massachusetts

Application October 8, 1957, Serial No. 48,018

Term of patent 14 years

(Cl. D14—3)

Fig. 1

Fig. 2

Fig. 3

Fig. 1 is a perspective view of an automobile body embodying my new design;

Fig. 2 is a side elevational view of the automobile body of Fig. 1; and

Fig. 3 is a fragmentary perspective view thereof.

The dominant features of my new design are shown in full lines in the drawings.

I claim:

The ornamental design for an automobile body, substantially as shown and described.
